UNITED STATES PATENT OFFICE.

LANSING ONDERDONK, OF NEW YORK, N. Y., ASSIGNOR TO UNION SPECIAL MACHINE COMPANY, OF CHICAGO, ILLINOIS, A CORPORATION OF ILLINOIS.

BLINDSTITCH SEWING-MACHINE.

1,123,575.

Specification of Letters Patent. Patented Jan. 5, 1915.

Application filed July 21, 1903. Serial No. 166,469.

To all whom it may concern:

Be it known that I, LANSING ONDERDONK, a citizen of the United States, residing at New York, in the county of New York, State of New York, have invented certain new and useful Improvements in Blindstitch Sewing-Machines, of which the following is a description, reference being had to the accompanying drawing and to the letters and figures of reference marked thereon.

My invention relates to an improvement in blind stitch sewing machines.

The particular object for which the present machine has been designed, is to provide a blind stitch sewing and ruffling machine, for producing the blind stitch ruffled seam, illustrated in patent granted C. McNeil, on the 20th day of January, 1903. No. 718,654, in which a piece of fabric is ruffled, and secured to a body fabric by blind stitching, the stitches passing through the body fabric, and the bases only of the ruffles, leaving the tops of the ruffles free and open, no stitches appearing on the faces of the ruffles. In adapting a machine for accomplishing the function above mentioned, however, several other features have developed, which are of value in the art of blind stitch sewing machines, without regard to whether a ruffling device is used therewith or not and these features I have hereinafter claimed.

The invention consists in the matters hereinafter described and referred to in the appended claims.

The invention is illustrated in the accompanying drawings, in which,

Figure 1 is a perspective view of a blind stitch sewing machine, embodying my invention; Fig. 2 is a detail top plan view, illustrating the mechanism for operating the looper; Figs. 3 and 4 are end views of the machine, showing the ridge-forming or crimping rib, the presser foot and the looper and needle in extreme position; Figs. 5 and 6 represent details of the position of the needle and looper in forming the stitch; Fig. 7 is a view representing the path of movement of the looper; Fig. 8 is a detail view of the ridge forming rib.

In these drawings, A represents the standard of the machine; B the gooseneck or overhanging arm; C the cylindrical bed

plate, containing the feed shafts which impart the rise and fall and forward and backward movements to the feed dog D.

Only the shaft for giving the forward and backward movements to the feed dog is herein illustrated, and that in dotted lines at E, the shaft for giving the rise and fall not being illustrated, except its end, as shown at F. These shafts are driven by eccentric and rod connections G, G, from the driving shaft H, which is journaled in the overhanging arm or gooseneck B, and is driven from the belt wheel I.

At its outer end which projects through the head of the machine, the driving shaft is provided with a crank K, which has a pivoted link connection L, with the elbow lever M, journaled on a stud N, on the head of the machine, and which carries at its lower end, means for the attachment of a curved needle, n, which in the rotation of the main shaft H reciprocates in the line of feed through the goods, which are preferably crimped by the cooperative action of the presser foot P, having a transverse V-shaped groove v in its under side, and the ridge-forming rib O, arranged transversely of the feed, or lengthwise of the bed plate.

The ridge-forming rib 4 is provided with longitudinal spaced slots O', and the feed dog D extends into these slots and engages the material to be stitched for feeding the same. The needle enters the material directly above the center of the crimping rib, as shown in Figs. 3 and 4, and, therefore, will enter the material directly over the part of the crimping rib between the slots O', O'. The feed dog, as above described, has a rising and falling and forward and backward movements. In other words, it is of the usual four-motion feed type, and engages the fabric both in advance and in rear of the crimping ridge.

When the feed dog is raised into engagement with the material, it lifts the same off the work support, and this upward movement of the feed dog, followed by the lateral movement, in a measure carries the material over the crimping ridge.

Near the front end of the driving shaft H is arranged an eccentric Q embraced by a strap on a connecting rod R, which at its oppo-

site end embraces the ball stud *a* on the crank *b*, secured to the shaft *S*, journaled in the head of the machine. At its upper end the shaft is provided with an arm or crank 5 *T*, having at its opposite end a link connection *c* with the crank *d* on the upper end of the shaft *e* supporting the looper *l*. This looper may or may not carry a thread and is arranged to oscillate in a direction opposite 10 the direction of movement of the needle *n*.

U represents the arm supporting the ruffler blade *f*. This arm is secured to the shaft *g*, pivoted on the bed plate of the machine, which shaft has an upwardly curved 15 slotted arm *h*, to which is adjustably secured the arm *W* pivoted to the arm *X* secured to the feed shaft *E*. In this way, motion is imparted to the ruffler blade, the amount of throw being regulated by the adjustment shown. In one use of my invention 20 the body fabric 1, is placed over the top of the ruffler blade, and the fabric 2 to be ruffled, is placed under the ruffler blade and against the cylindrical bed plate, the 25 stitches pass only through the bases of the ruffler and through the body fabric, or if no body fabric be used, only through the bases of the ruffles.

Having thus described my invention, 30 what I claim and desire to secure by Letters Patent, is:—

1. A sewing machine including in combination, a work support, means for crimping the fabric in a direction transversely of the line of feed, stitch-forming mechanism including a needle mounted above the work support and reciprocating back and forth in a line at an angle to a vertical plane, cutting the line of feed at right angles, where- 35 by the needle is caused to enter the crimped fabric and emerge on the same face of the fabric, a feeding mechanism including a feed dog adapted to engage the material at the stitching point both in advance and in rear 40 of said crimping means, means for raising and lowering said feed dog, and means for moving said feed dog back and forth.

2. A sewing machine including in combination, a work support having a crimping rib extending substantially at right angles to the line of feed, said crimping rib having slots for the feed dog formed therein, a feeding mechanism including a feed dog adapted to extend through said feed slots 55 and engage the material at the crimp therein, means for raising and lowering said feed dog, means for moving said feed dog back and forth, and stitch-forming mechanism including a needle mounted above the work support and reciprocating back and forth substantially in the line of feed, said needle being so disposed as to enter the material in the direction of feed of the fabrics.

3. A blind stitch sewing machine having

stitch-forming mechanism, including a 65 needle reciprocating above the work support in a direction to enter the fabric substantially in the line and the direction of the feed, a looper coöperating therewith to form stitches also arranged above the work support, and means for crimping the work, including a ridge-forming rib arranged transversely of the feed, and a presser foot having a transverse groove fitting over said ridge-forming rib; substantially as de- 75 scribed.

4. A blind stitch sewing machine, having stitch-forming mechanism, including a needle reciprocating above the work support and entering the fabric substantially 80 in the line and in the direction of the feed and emerging from the same face of the fabric, a looper coöperating therewith to form stitches, means for crimping the work, and a ruffling device; substantially as described. 85

5. A sewing and ruffling machine, embodying a feeding mechanism, a work support, a needle entering and emerging on the same face of the fabric, and means for reciprocating it so that said needle enters the 90 fabric substantially in the line and in the direction of the feed, a looper coöperating therewith to form stitches, and a ruffling device, whereby a fabric may be ruffled and the ruffles secured by stitches passing 95 through the bases only of the ruffles; substantially as described.

6. A blind stitch sewing machine, embodying a feeding mechanism, a work support, a needle entering and emerging on the 100 same face of the fabric, means for reciprocating it so that said needle enters the fabric substantially in the line and in the direction of the feed, a looper coöperating therewith to form stitches, both said needle and 105 looper being arranged and operating above the work support, a ruffling device, means for operating the same, and means for crimping the goods transversely of the direction of feed; substantially as described. 110

7. A blind stitch sewing machine, embodying a feeding mechanism, a work support, a needle entering and emerging on the same face of the fabric, means for reciprocating it so that said needle enters the 115 fabric substantially in the line and in the direction of the feed, a looper coöperating therewith to form stitches, both said needle and looper being arranged and operating above the work support, a ruffling device, means for operating the same, means for adjusting the throw of the ruffling device, and means for crimping the goods transversely of the feed; substantially as described.

8. The combination with a work support, a ruffling blade, means for operating said ruffling blade, and stitch-forming mecha-

nism including a needle moving substantially in a line parallel with the movements of the ruffling blade, and in the same direction therewith, whereby the fabric gathered 5 by the ruffling blade is entered by said needle, and the needle emerges on the same face of the fabric in which it entered.

In testimony whereof I affix my signature, in presence of two witnesses.

LANSING ONDERDONK.
